UNITED STATES PATENT OFFICE.

ANDREW WEISS, OF CLEVELAND, OHIO.

WASHBOARD.

No. 851,110.

Specification of Letters Patent.

Patented April 28, 1907.

Application filed December 13, 1906. Serial No. 347,624.

To all whom it may concern:

Be it known that I, ANDREW WEISS, a citizen of the United States, residing at Cleveland, in the county of Cuyahoga and State of Ohio, have invented new and useful Improvements in Washboards, of which the following is a specification.

This invention relates to washboards and has for its object to provide improved means for preventing water from running behind the face plate of the board, and also for preventing the collection of dirt between the face plate and back.

A further object of the invention is to provide improved means for holding the top edge of the corrugated face plate, so as to prevent possible injury to the hands of the user caused by the loosening of said edge.

The means for effecting the above objects also serve to provide an improved soap holder.

The invention is illustrated in the accompanying drawings, in which—

Figure 1 is a perspective view of the board. Fig. 2 is a back view. Fig. 3 is a longitudinal section. Fig. 4 is a cross section on the line 4—4, Fig. 3.

Referring specifically to the drawings, the frame of the washboard consists of side pieces 6, a head board 7, a top rail 8, and a bottom bar 9, all secured together by nailing or dove-tailing or in any other suitable manner. The feet of the side pieces are preferably rounded as indicated at 10 so as to have no sharp corners to tear the clothes and to allow the board to be more easily moved around.

The inner sides or faces of the side pieces 6 are grooved to receive the edges of the corrugated metal face plate 11, and also recessed or mortised at the ends of said groove to receive the ends of the bottom bar 9 and a top bar 12, which latter is located just below the lower edge of the head board 7. The corrugated metal plate is supported by a plurality of longitudinal back bars 13, the ends of which are set in rebates 14 in the edges of the top and bottom bars. These bars 13 are also supported at the middle by a middle cross bar 15 the ends of which are set in mortises in the

side pieces 6 and which have recesses at 15* through which the lengthwise bars 13 extend. 50

At the upper end of the face plate 11 is a guard or retaining plate consisting of a piece of sheet metal indicated at 16 which lies over or upon the upper edge of the face plate 11 and serves to hold said plate down against 55 the top bar 12, the lower edge of the plate 16 being fitted into the upper corrugation in the face plate 11 so that said edge will not catch the hands or the clothes during the act of rubbing. The side edges of the plate 16 are set 60 in the grooves in the side pieces 6. At the top of the face plate the guard 16 is folded upon itself at 17, forming an up-standing and outwardly projecting flange which serves to retain soap placed upon the head board 7. 65 The flange is perforated at 18 to allow water to flow from the soap holder down onto the front of the board. From the flange the plate 16 is bent to extend toward the back of the board and through the slit or space between the head board 7 and the top bar 12, and the back edge of said plate is then turned up at 19 to fit behind the board 7, extending up behind said board a sufficient distance to prevent water from flowing through behind 70 the head board. Any water which may splash up on the front of the head board will be collected in the plate at the bottom thereof and escape through the openings 18 onto the front of the face plate. This will prevent 75 water leaking through the board and wetting the clothes of the washwoman.

It will be seen that the plate 16, bent and formed as stated, serves to hold the upper edge of the corrugated face plate, and also to 80 form a soap holder at the bottom of the head board, and also to form a shield which prevents leakage through behind the head board. The skeleton back or construction produced by the bars behind the face plate 90 prevents the collection of dirt, as between the face plate and the ordinary solid back in common use.

I claim:

1. A washboard having a head board, a top bar below the same, with a narrow open-

ing therebetween, a face plate the top edge of which rests upon the bar, and a guard plate which laps the said edge of the face plate and extends through said opening between the 5 lower edge of the head board and top bar and up behind said board, and in contact with the said edge and the back of the board.

2. A washboard having a head board, a face plate supported below the same, and a 10 guard plate which laps the top of the face

plate and extends behind the head board and has a perforated flange under the said board, forming a soap holder.

In testimony whereof I have signed my name to this specification in the presence of 15 two subscribing witnesses.

ANDREW WEISS.
